LUMINAIRE

William T. Eppard, Arcadia, Calif., assignor to Kim Lighting & Manufacturing Company, Inc., El Monte, Calif., a corporation of California

Continuation-in-part of design application Ser. No. 2,950, July 6, 1966. This application June 28, 1967, Ser. No. 7,632

Term of patent 14 years

(Cl. (D48—31)

FIG. 1 is a side elevation of a luminaire according to the invention;

FIGS. 2 and 3 are left and right-hand elevations respectively of FIG. 1; and

FIG. 4 is a bottom plan view of FIG. 1, the top plan view being substantially identical except for the omission of the base.

The broken line showing of a support pole throughout the figure is for illustrative purposes only.

This is a continuation-in-part of applicant's co-pending patent application No. D2,950, filed July 6, 1966, now abandoned.

I claim:

The ornamental design for a luminaire, as shown and described.
